UNITED STATES PATENT OFFICE

94,750

DESIGN FOR A PICTURE FRAME

Abraham Golden, Chicago, Ill.

Application December 5, 1934, Serial No. 54,279

Term of patent 3½ years

To all whom it may concern:

Be it known that I, Abraham Golden, a citizen of the United States, residing at Chicago, Cook County, and State of Illinois, have invented a new, original, and ornamental Design for Picture Frames, of which the following is a specification, reference being had to the accompanying drawing, forming part thereof.

Fig. 1 is a front elevation of a picture frame showing my new design and

Fig. 2 is an enlarged detail cross-section taken on the line 2—2 of Fig. 1.

In the drawing, the surface ornamentation fragmentarily shown on the two parallel strips is repeated throughout the same.

I claim:

The ornamental design for a picture frame, as shown and described.

ABRAHAM GOLDEN.
